United States Patent Office

Des. 230,641
Patented Mar. 5, 1974

230,641

FUEL NOZZLE UNIT

Dorian Farrar Mowbray, 6 Cheveley Gardens,
Burnham, Buckinghamshire, England

Filed Nov. 2, 1970, Ser. No. 25,763

Claims priority, application Great Britain Oct. 14, 1970

Term of patent 14 years

Int. Cl. D15—01

U.S. Cl. D77—1 A

FIG. 1

FIG. 2

FIG. 3

FIG. 4

FIG. 5

FIG. 1 is a perspective view of a fuel nozzle unit showing my new design.

FIG. 2 is an elevational view taken from one side thereof.

FIG. 3 is an elevational view taken from the side opposite that shown in FIG. 2.

FIG. 4 is an elevational view taken from one end thereof.

FIG. 5 is an elevational view taken from the end opposite that shown in FIG. 4.

I claim:

The ornamental design for a fuel nozzle unit, as shown.
